UNITED STATES PATENT OFFICE.

GEORGE MCGREGOR, OF CINCINNATI, OHIO.

IMPROVEMENT IN CAR-SEAT LOCKS.

Specification forming part of Letters Patent No. 40,113, dated September 29, 1863.

To all whom it may concern:

Be it known that I, GEORGE MCGREGOR, of Cincinnati, in the county of Hamilton and State of Ohio, have invented a new and Improved Car-Seat Lock; and I do hereby declare that the following is a full, clear, and exact description of the same, reference being had to the accompanying drawings, forming part of this specification, in which—

Figure 1 represents an inside elevation of my invention. Fig. 2 is a longitudinal section of my invention taken in the plane indicated by the line x x , Fig. 1. Fig. 3 is a transverse section of the same, the line y y , Fig. 1, indicating the plane of section.

Similar letters of reference in the three views indicate corresponding parts.

The object of this invention is a latch peculiarly adapted for locking the backs of car-seats in either position in which the same may be brought, and arranged in such a manner that the same can be made at a trifling expense, requiring a comparatively small quantity of metal, and that it is strong, durable, and not liable to get out of order.

The nature of my invention and its particular advantages will be readily understood from the following description:

A represents a case, cast of brass or any other suitable material, and provided with three (or more) holes, a , to admit screws, which serve to fasten the same to the desired spot. A recess, b , in the front end of the case forms the guide for the head of the bolt B, the body of which is situated in the cavity c , and a bridge, d , forms the guide for the shank e of said bolt. A shoulder, f , behind the head of the bolt prevents the same shooting out any farther than desirable, and a spiral spring, g , which is wound round the shank e , has a tendency to force the bolt out. The head of the bolt, is flat and beveled or rounded off both ways, so that it drops into a suitable catch both ways with equal facility. The force of the blows as the bolt strikes the catches on either side is exerted edgewise, and consequently a comparatively thin bolt is able to withstand said blows without injury.

The key C is made hollow, and it is introduced through the key-hole h in the case, being guided by the pin i . This pin is cast solid with the case, and it is cut out and rounded off by a suitable cutter. It projects from a lug, j , on the inner side of the case, and it is filed off flush with the outer surface of said case.

The bit k of the key is made with two shoulders, as clearly shown in Fig. 3, and it acts on a recess, l , in the body of the bolt. This body is hollowed out to make room for a pin, m , which projects from the interior of the case. If a key should be inserted into the latch with a bit of different shape from that shown in Fig. 3, said bit will strike the pin m , and the unlocking of the latch is prevented. The proper shape of the bit is dependent upon the position of the lug j and pin m in relation to each other, and by the position of the lug j it is indispensable that the bit shall project beyond the end of the shank of the key, so that its point is enabled to come in contact with the recess l in the body of the bolt.

This latch is particularly intended to be attached to the arms on which the backs of car-seats swing, and it serves to secure the back of the seat in either position. It is obvious, however, that it may be used for locking or fastening other articles besides car-seats, and on account of its great cheapness it can be applied with advantage to take the place of other latches of a more expensive or less durable construction.

What I claim as new, and desire to secure by Letters Patent, is—

The arrangement and combination of the case A with lug j and pin m , hollow key C, with double-shouldered bit k and spring-bolt B, all constructed and operating in the manner and for the purpose shown and described.

GEORGE MCGREGOR.
